WEATHER STRIP

Howard H. Turner, Inglewood, Calif., assignor of twenty-four and one-half per cent to C. E. Joslin and twenty-four and one-half per cent to M. E. Joslin, both of Inglewood, Calif.

Application January 2, 1940, Serial No. 312,013

4 Claims. (Cl. 20—68)

My invention relates to a tensioned weather strip and the principal object of the invention is to provide means for adjusting tension for varying the tension on the weather strip.

Another object of the invention is to provide means for adjusting the tension on the weather strip, which means is accessible when the weather strip is in its operative position.

This invention also comprises novel details of construction and novel combinations and arrangements of parts, which will more fully appear in the course of the following description. However, the drawing merely shows and the following description merely describes an embodiment of the present invention, which is given by way of illustration or example only.

Reference is hereby made to my co-pending application Serial No. 285,973, filed July 22, 1939, on Weather striping, for matter shown and described but not claimed herein.

In the drawing, like reference characters designate similar parts in the several views.

Figure 1 is an elevation of a window frame with sashes therein, to which has been applied an embodiment of my invention.

Figure 2 is an enlarged, broken section taken on the line 2—2 of Figure 1.

Figure 3 is a transverse, broken section taken on the line 3—3 of Figure 2.

Figure 4 is an enlarged, longitudinal, broken section of a corner of a sash to which an embodiment of my present invention has been applied.

Figure 5 is a section taken on the line 5—5 of Figure 4.

Figure 6 is a broken, perspective view of a detail.

Figure 7 is a broken elevation of a detail.

Referring more in detail to the drawing, the reference numeral 6 generally designates a window frame in which sashes 7 and 8 are slidably hung. The jambs of the window frame are shown at 9. Window glass 10 is held by putty 12 in the stiles 13 and rails 14 of each sash.

The stiles are routed and are provided with different sizes and shapes of aligned bores. The first bored section 15 is cylindrical and provides a bearing for a pin 16 that is cross slotted at one end 17, as best shown in Figure 6, and is threaded at the other end, as shown at 18. A circular, integral shoulder 19 is fastened on the pin 16 in an enlarged, square bore 20.

A nut 21 having a square periphery fits in the bore 20. The stile 13 is routed longitudinally at its outer edge, as shown at 22, and a weather strip 23 is disposed longitudinally in the rout 22. The

depth of the rout 22 is substantially the same as the depth of the strip 23. A coil spring 24 is arranged in the bored portion 20 between the nut 21 and the rear face of the weather strip 23.

The jamb 9 has an angular recess 25 and the weather strip 23 has an angular, ridge-like projection 26 that projects into the recess 25. The angle of the projection 26 is preferably a narrower angle than that of the recess 25.

Metal plates 27 are bolted at the ends of the stiles, to close the ends of the longitudinal routs 22, thereby preventing longitudinal displacement of the weather strips 23 during movement of the window sash.

The bore 15 is countersunk at the opposite end from the weather strip, to receive a bottomless cup 28. Prongs 29 provided by the cross slotted end 17 of the pin 16 are swaged outward against the inner face of the cup 28, as perhaps best shown in Figure 7. The cup 28 is thereby held in position and the pin 16 is held against movement to the right in Figures 2 and 4. The shoulder 19 abutting against the end of the bore 20 prevents movement of the pin 16 to the left in Figures 2 and 4.

The notched end 17 of the pin 16 provides two notches 30 and 31 at right angles to each other. The notch 31 is the deeper of the two notches. When the end 17 of the pin 16 is arranged in the cup 28, prongs 32, 33, 34 and 35 are swaged outwardly. The swaging is effected substantially to the depth of the shallower notch 30. This leaves the notch 31 for the reception of a screw-driver. In Figure 2 the deeper notch 31 is shown in elevation, and in Figure 4 the notch 30 is shown in elevation. In the latter view, the deeper notch 32 is shown by a broken line. The cross arrangement and the relative depth of the notches is best shown in Figure 6.

To adjust the tension of the springs 24 behind the weather strips 23, a screw-driver is applied to the notched end 17 of the pin 16. Turning the pin 16 causes the nut 21 to move one way or another, depending upon the direction of rotation of the pin 16. The tension on the springs 24 is increased or decreased, depending upon whether the nuts 21 are moved to or from the weather strips 23. Thus it can be seen that the tension of the weather strips may be varied even though the sashes and weather strips are in their operative positions.

This invention is especially of value when assembling sashes in frames in new construction, or when reassembling is done by reason of repair or reconstruction. In any of these events, the

pin 16 may be turned until the nut 21 is at its extreme left position, in Figure 2. Then the weather strip may be easily pushed into the longitudinal rout 22, until the strip is flush with the sides thereof. The sash and its weather strips may thus easily be inserted into the frame. Thereupon the pins 16 are turned, by means of a screw-driver, until the desired amount of tension is placed in the springs 24. This desired amount may be readily determined by ascertaining whether the springs bearing against the weather strips cause the sashes to be firmly held in adjusted positions and yet permit the sashes to be moved to different positions without undue effort. The present invention is also of value in taking up wear on the weather strips, after they have been used for a considerable period.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications which may fall within the scope of the appended claims.

Having thus described my invention, what I claim and desire to secure by Letters Patent is:

1. In combination with closure elements, a weather strip movably supported on one of said elements to bear against the other element, spring means disposed with one end freely engaging the strip and tending to urge the strip into such bearing position, a threaded pin rotatable through a portion of said element, a threaded abutment arranged on the pin and engaging the other end of the spring to adjust the tension on the spring, means to prevent turning movement of the abutment with the pin, a shoulder on the pin engaging one side of the said portion of the element to prevent lengthwise movement of the pin out of position under action of the spring, and the pin having an adjusting head opposed to the shoulder and engaging the opposite side of the said portion of the element to prevent movement of the pin in the opposite di-

rection, the adjusting head being accessible exteriorly of the supporting element in use.

2. A weather strip, a supporting element with respect to which said strip is movable, spring means disposed with one end freely, yieldingly engaging the strip and tending to urge the strip outwardly of said element, a threaded pin rotatably supported against lengthwise movement in said element, a threaded abutment arranged on the pin and engaging the other end of the spring to adjust the tension on the spring, means to prevent turning movement of the abutment with the pin, the pin having an outer slotted end and having outwardly swaged portions between its slots to limit longitudinal movement of the pin in one direction.

3. A weather strip, a support on which said strip is movable to an outer bearing position, spring means tending to urge the strip into such bearing position, a threaded pin, a threaded abutment arranged on the pin to adjust the tension on the spring, and the pin having its outer end cross slotted, the slots being of different depths, also having outwardly swaged prongs at the end thereof between the cross slots, inclined with respect thereto substantially to the depth of the shallower slot.

4. A window sash having a groove and a bore at right angles to the groove, a weather strip 30 slidable in said groove for movement outwardly of the sash, a threaded pin having rotatable bearing through a portion of the sash and extending at its inner end axially of, and within, the sash bore, a follower threaded on said pin 35 and slidable and non-rotatable in said bore, a spring compressed between the follower and the weather strip with its outer end freely engaging the strip for constantly applying its tension against the latter, means holding the pin against lengthwise movement in the pin bearing portion of the sash including a cross-slotted head at the outer exposed end of the pin having swaged extensions between the slots, and a conical thimble in a surface of the pin bearing portion of the sash and in which the said swaged end of the pin is movably seated.

HOWARD H. TURNER.
